SCREEN DOOR GRILLE

Walter A. Curtze, Erie, Pa.

Application January 9, 1956, Serial No. 39,654

Term of patent 14 years

(Cl. D54—2)

FIG. 1

FIG. 2

Fig. 1 is a front elevational view of the screen door grille showing my new design; and

Fig. 2 is a top edge view.

The characteristic features of my design for the screen door grille disclosed reside in the corner members having the configurations shown. The corner members have plain backs and, except for the lack of ornamentation, have the same appearance from the rear as from the front.

I claim:

The ornamental design for a screen door grille, substantially as shown and described.
